PROTECTIVE SHOULDER CAP

Leif H. Skottheim, Malung, Sweden, assignor to
Jofa AB, Malung, Sweden

Filed Oct. 10, 1974, Ser. No. 513,850

Term of patent 14 years

Int. Cl. D2—02

U.S. Cl. D2—27

FIG. 1 is a top, front and inner end perspective view of a protective shoulder cap showing my new design.

FIG. 2 is a bottom, rear and inner end perspective view of said protective shoulder cap.

FIG. 3 is a bottom, front and outer end perspective view thereof.

FIG. 4 is a top, rear and outer end perspective view thereof.

I claim:

The ornamental design for a protective shoulder cap, as shown.
